UNITED STATES PATENT OFFICE

158,149

SELF-CONTAINED AIR-CONDITIONING UNIT

Carl W. Sundberg, Detroit, Mich., assignor to Carrier Corporation, Syracuse, N. Y., a corporation of Delaware

Application February 16, 1949, Serial No. 1,207

Term of patent 14 years

(Cl. D62—4)

To all whom it may concern:

Be it known that I, Carl W. Sundberg, a citizen of United States, residing at Detroit, in the county of Wayne, State of Michigan, have invented a new, original, and ornamental Design for a Self-Contained Air-Conditioning Unit, of which the following is a specification, reference being had to the accompanying drawing, forming part thereof, in which

The figure is a perspective view of a self-contained air-conditioning unit showing my new design.

The side of the unit not shown is the same as the side shown.

I claim:

The ornamental design for a self-contained air-conditioning unit, substantially as shown and described.

CARL W. SUNDBERG.
